(57) **CLAIM**

The ornamental design for a hose stand with decorative shelf and spout support, as shown and described.

DESCRIPTION

FIG. 1 is a right side perspective view of one embodiment of a hose stand with decorative shelf and spout support; FIG. 2 is a front view of the embodiment in FIG. 1; FIG. 3 is a back view of the embodiment in FIG. 1; FIG. 4 is a left side view of the embodiment in FIG. 1; FIG. 5 is a right side view of the embodiment in FIG. 1; and, FIG. 6 is a top side view of the embodiment in FIG. 1. The broken lines represent portions of the hose stand with decorative shelf and spout support that form no part of the claimed design.
